UNITED STATES PATENT OFFICE.

HARRY BARD, OF MILLVILLE, NEW JERSEY, ASSIGNOR TO MILLVILLE MACHINE COMPANY, OF MILLVILLE, NEW JERSEY, A CORPORATION OF NEW JERSEY.

PLUNGER FOR GLASS-BLOWING MACHINES.

No. 805,335.

Specification of Letters Patent.

Patented Nov. 21, 1905.

Application filed April 7, 1903. Serial No. 151,477.

To all whom it may concern:

Be it known that I, HARRY BARD, a citizen of the United States, residing at Millville, New Jersey, have invented certain Improvements 5 in Plungers for Glass-Blowing Machines, of which the following is a specification.

My invention relates to glass-blowing machines, and more particularly to plungers employed for the preliminary recessing or pressing 10 of the glass in the blank or press molds in the manufacture of bottles having necks of contracted area.

My invention is fully shown in the accompanying drawings, in which—

15 Figure 1 is a view of a blank or press mold with the plunger within the mass of glass charged into the same. Fig. 2 is a full-sized view of the plunger and its connected parts in section. Fig. 3 is a sectional plan view on 20 the line *a a*, Fig. 2; and Fig. 4 is a perspective view of the separable part of the plunger.

25 In the blowing of hollow glassware by machinery it is necessary, of course, to insert a plunger in the mass of glass within the press-mold for the purpose of forming the neck and head of the bottle and the preliminary recess to receive the air to finish the article. When 30 making bottles or other hollow ware having contracted openings, it is necessary to provide

35 a straight plunger, as such plunger finishes the internal wall of the neck and head. In using a straight plunger, however, great difficulty is experienced in withdrawing such plunger from the mass of glass after it has 40 been entered into the same; and the object of my invention is to overcome this difficulty and insure the ready and immediate withdrawal of the plunger after it has effected the preliminary recessing of the glass. To prevent 45 the plunger sticking in the mold, such sticking being due normally to a vacuum between the plunger and the mass of glass, I make the plunger 1 hollow, with an opening 2 extending through the same and communicating near the upper part of the plunger to the atmosphere through an opening 3. In the lower part of this opening or recess 2 a movable member 4 is carried, which member is 50 grooved at 5 and is provided with an enlarged

55 opening 6, through which passes a pin 7, securing it to the plunger. This arrangement provides for a certain amount of movement between said plunger and the movable piece.

This movable piece has an enlarged head 8, shaped like the head of an ordinary screw, 55 and this fits the beveled portion 9 in the end of the plunger. When the plunger is inserted in the glass, the movable piece is pressed up into the tubular portion of the plunger and stays there until the plunger is started out of 60 the glass. At this time the slightest movement of the plunger, which might even cause movement of the glass, is sufficient to separate the plunger from the movable piece, which necessarily remains in its lower position 65 due to the force of gravity, and this slight separation between the parts is sufficient to admit air from the atmosphere which passes through the tubular portion of the plunger, thereby breaking the vacuum created by 70 the plunger when it is inserted in the glass, and the plunger may be then removed without difficulty. The movable piece is not necessarily of the shape shown, but must be so shaped and arranged as to provide for the passage 75 of air around the same and must have a head exactly fitting the plunger when the two are brought together as they are forced into the glass. Instead of having simply a tapered head the upper portion of the movable piece may also be tapered, and in some instances such piece may be tapered from end to end.

Having thus described my invention, I claim and desire to secure by Letters Patent— 85

The combination of a hollow, elongated plunger for use with glass-blowing machines, having an upper opening communicating with the atmosphere and a lower opening with a flared or beveled mouth, a short movable plug fitting the hollow bore of the plunger at its lower end, said plug being grooved for the passage of air, a head carried by said plug and shaped to fit the flaring mouth of the plunger and serving to fully close the lower opening, 90 and a pin carried by the plunger and confining the plug to the same, said plug being slotted to receive the pin and provide for slight movement with respect to the plunger. 95

In testimony whereof I have signed my name 100 to this specification in the presence of two subscribing witnesses.

HARRY BARD.
